**CRADLE FOR POSITIONING PATIENT FOR
RADIOLOGICAL DIAGNOSIS OR THERAPY**

Wesley A. Mowrer, Northfield, Ohio, assignor to
Bandel, Inc., Cleveland, Ohio

Filed Feb. 27, 1970, Ser. No. 21,661

Term of patent 14 years

Int. Cl. D24—02

U.S. Cl. D83—1

FIG.1

FIG.2

FIG.3

FIG.4

FIG.5

FIG.6

FIG. 1 is a perspective view of a cradle for positioning patient for radiological diagnosis or therapy, showing my new design;

FIG. 2 is a top plan view thereof;

FIG. 3 is a side elevation view thereof;

FIG. 4 is a bottom plan view thereof;

FIG. 5 is a head end view thereof; and

FIG. 6 is a foot end view thereof.

The broken lines are shown for illustrative purposes only and form no part of the claimed design.

I claim:

The ornamental design for a cradle for positioning patient for radiological diagnosis or therapy, as shown and described.
